(57) **CLAIM**

The ornamental design for a dog trainer, as shown and described.

DESCRIPTION

FIG. 1 is a front, top, right side perspective view of a transmitter, of the dog trainer, shown separately for ease of illustration;

FIG. 2 is a rear, bottom, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is a front, top, right side perspective view of a receiver, of the dog trainer, shown separately for ease of illustration;

FIG. 10 is a rear, bottom, left side perspective view thereof;

FIG. 11 is an enlarged front elevation view thereof;

FIG. 12 is an enlarged rear elevation view thereof;

FIG. 13 is an enlarged left side elevation view thereof;

FIG. 14 is an enlarged right side elevation view thereof;

FIG. 15 is an enlarged top plan view thereof;

FIG. 16 is an enlarged bottom plan view thereof; and,

FIG. 17 is a perspective view of transmitter and receiver of the dog trainer.

The broken lines in the drawings illustrate portions of the dog trainer that form no part of the claimed design.

1 Claim, 17 Drawing Sheets
